Primary Examiner — Jennifer Rivard*Assistant Examiner* — April Rivas(74) *Attorney, Agent, or Firm* — Bruce S. Shapiro(57) **CLAIM**

The ornamental design for a toolbox, as shown and described.

DESCRIPTION

FIG. 1 is a perspective view of the top side of my new design.

FIG. 2 is a perspective view of the bottom side thereof.

FIG. 3 is a front side elevational view thereof.

FIG. 4 is a back side elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken lines illustrate portions of the toolbox and form no part of the claimed design.
